COMBINED COLOR TELEVISION SET AND SLIDE THEATER OR SIMILAR ARTICLE

James T. Asaki, Batavia, N.Y., assignor to Sylvania
Electric Products Inc., a corporation of Delaware

Filed Aug. 13, 1968, Ser. No. 13,122

Term of patent 14 years

Int. Cl. D14—03; D16—03

U.S. Cl. D56—4

Fig. 1

Fig. 2Fig. 3

FIG. 1 is a top perspective view of a combined color television set and slide theater or similar article illustrating my new design;

FIG. 2 is a front perspective view thereof; and
FIG. 3 is a rear perspective view thereof.

The end portion of the combined color television set and slide theater or similar article not illustrated is symmetrical with the end portion of FIGS. 2 and 3. The dominant features of my design are shown in the solid lines.

I claim:

The ornamental design for a combined color television set and slide theater or similar article, as shown and described.
